ERASER

Rudolph George Roesch, Syracuse, N. Y., assignor
to The Eraser Company, Inc., Syracuse, N. Y., a
corporation of New York

Application August 3, 1940, Serial No. 350,766

7 Claims. (Cl. 120—36)

This application is a continuation-in-part of my copending application Serial No. 175,867, filed November 22, 1937, now Patent No. 2,210,432 issue of August 6, 1940, for an Eraser.

My invention has to do with improvements in the case and propelling apparatus for a propell-retract eraser of the class described in the above identified copending application.

One of the objects of my invention is to provide a simple, inexpensive eraser holder constructed of a plurality of parts rotatably joined together.

Another object of my invention is to provide a hollow eraser case having a substantially cylindrical cavity therein for holding the eraser, said cavity being provided with integral guides for directing and supporting throughout its length a relatively long, substantially flat eraser.

Still another object of my invention is to provide a simple inexpensive separable connection between the propelling mechanism and the eraser.

A still further object of my invention is to provide a simple bent wire connector for releasably joining a substantially flat eraser to the propelling mechanism.

Other objects and advantages of my invention will appear from the following specification taken in conjunction with the accompanying drawing, in which:

Figure 1 is a perspective view of an eraser holder embodying the various features of this invention.

Figure 2 is an enlarged longitudinal central sectional view of the same.

Figure 3 is a perspective view illustrating various parts of the eraser shown in Figures 1 and 2 with the parts arranged in exploded relation to each other, certain of the parts being shown broken away and in section.

Figure 4 is a transverse sectional view taken on the line 4—4 of Figure 2.

Figure 5 is a transverse sectional view taken on the line 5—5 of Figure 2.

Figure 6 is a transverse sectional view taken on the line 6—6 of Figure 2.

Figure 7 is a perspective view of a long, flat eraser adapted for use in my eraser holder and showing a simple wire connector for joining the eraser to the propelling mechanism.

Figure 8 is a plan view of the forming dies used in forming up the wire connector shown in Figure 7.

Figure 9 is an elevation, part being in section and part being broken away, illustrating the

forming of a wire connector by means of the dies illustrated in Figure 8.

Figure 10 is an elevation, part being in section, taken on the line 10—10 of Figure 9.

Figure 11 is a plan view, part being broken away, of an eraser with the wire connector in place.

The eraser illustrated in Figures 1 to 6, inclusive, comprises primarily a tubular case or holder 12, an erasing element or refill 13, and suitable operating means comprising a screw 14 coacting with the erasing element for moving the same with respect to said case.

The case or holder 12, in this instance, is composed of three sections, an eraser housing section 15, a propeller barrel 16 and an intermediate section or ferrule 17. The eraser housing 15 and barrel 16 are preferably composed of light molded material such as Bakelite, while the ferrule 17 is preferably composed of metal such as nickel plated brass or other suitable material. The ferrule 17 is constructed with a tubular or socket portion 18 of substantially the same outer diameter as the end portions 15 and 16 and a hub or boss portion 19 of less diameter than the socket 18 and which is arranged to extend from one end of the socket 18 in substantially coaxial relation therewith.

The socket 18 of the ferrule 17 is provided with internal threads 20 which are adapted to engage corresponding external threads 21 provided on the reduced inner end portion 22 of the eraser housing 15 for releasably securing the ferrule and housing 15 to each other. The hub portion 19 is provided with a circumferential groove 23 adjacent the outer end thereof. The inner wall of the groove 23 may be radial or at right angles to the axis of the hub 19. The outer wall 24 of the groove 23 is disposed at an angle to the axis of the hub 19 so as to provide a substantially V-shaped form to the groove 23.

A hollow sleeve 25 is rotatably mounted on the hub 19. The width of the sleeve 25 is slightly greater than the length of the hub 19 as measured from the portion 18 to the inner vertical wall of the groove 23. In other words, the outer edge of the sleeve 25 projects part way over the groove 23 when the sleeve 25 is mounted so as to abut against the socket 18 of the ferrule 17.

The sleeve 25 is secured on the hub 19 by means of the C-shaped clip 26. The clip 26, best illustrated in Figures 3 and 5, is shaped substantially in the form of an open sided square with the ends 27 bent slightly inward toward each other. After the sleeve 25 is placed on to the

hub 19 the clip 26 is slipped into the groove 23, the inward bend given to the end portions 27 being sufficient to frictionally retain the clip 26 in the groove 23. The outer surface of the sleeve 25 is provided with longitudinal substantially parallel ridges or corrugations 28 for a purpose presently to be described.

The ferrule 17 is provided with a substantially axially internally threaded bore to accommodate the screw member 14. One end of the screw member 14 is provided with a pair of diametrically opposed ears 30 which, in the preferred form, are formed integrally with the screw member 14. The opposite end of the screw member 14 is provided with a head 31 joined to the screw member by a neck portion 32, the head 31 and neck 32 being preferably integral with the screw member 14. After threading the screw member 14 in the ferrule 17, it is staked as at 33 to prevent unscrewing beyond a predetermined point for a purpose presently to be described.

The propeller barrel 16 is provided with a cylindrical bore 35, as illustrated in Figures 3 and 6. The diameter of the bore 35 is slightly greater than that of the screw member 14 so that the member 14 may slide freely therein. Extending outwardly from the cylindrical bore 35 are the diametrically opposed longitudinal grooves 36. The grooves 36 are designed to slidably accommodate the ears 30 of the screw member 14 so that rotation of the barrel 16 will rotate the screw 14. The inner end of the barrel 16 is provided with an enlarged cylindrical bore 37 of a diameter sufficiently smaller than the outside diameter of the sleeve 25 to permit the barrel 16 to be press-fitted on the sleeve 25. It is to be noted that the clip 26 is proportioned so that it just fits inside the cylindrical bore of the barrel 16 so that after said barrel is pressed in place on the sleeve 25, the clip 26 is permanently locked in the groove 23 as shown in Figure 5. It is thus obvious that the barrel 16 is rotatably joined to the ferrule 17 by means of the sleeve 25 which is securely held in place by the clip 26 in such fashion that there is no wobble or shake between the ferrule 17 and the barrel 16.

The eraser housing 15 of the case is flattened, as at 40, adjacent the outer end thereof and that end is provided with an oblong aperture 41 which opens into the interior cylindrical bore 42. As illustrated in Figures 2 and 4, a pair of diametrically opposed grooves 43 are provided extending outwardly from the bore 42 and extending substantially the entire length of the eraser housing 15. The grooves 43 terminate at the outer end to form the ends 44 of the oblong opening 41.

My eraser holder is adapted to utilize glass fibre erasers as described in my copending application Serial No. 175,867. The fibre glass eraser, more particularly described in the above mentioned copending application, comprises a substantially cylindrical bundle of glass fibres 50 suitably treated so as to be bound together and provided with an end cap 51. The cap 51 is secured to the bundle of glass fibres 50 by inserting the bundle 50 into the cylindrical portion 52 and then crimping the end thereof as illustrated. The cap 51 comprises a hollow substantially cylindrical body portion 52 which is provided with a smaller substantially cylindrical extension 53. The side wall of the extension 53 is provided with an opening 54 which is large enough to accommodate the head 31 of the screw member 14. A radially extending slot 55 is pro-

vided in the end plate of the extension 53 to accommodate the neck 32 of the screw member 14.

To insert the fibre glass eraser in the holder, the eraser housing 15 is unscrewed from the ferrule 17, the fibre glass eraser is partially inserted in the bore 42 of the housing 15 with the cap 51 projecting outward from the housing 15 so that the head 31 of the screw member 14 may be inserted into the opening 54 of the projection 53. The housing 15 is then screwed into the ferrule 17. The fibre glass eraser 50 may be propelled outward so as to project beyond the end slot 41 by holding the ferrule 17 and rotating the barrel 16 in a clockwise direction. The fibre glass eraser may be drawn back into the housing 15 by holding the ferrule 17 and rotating the barrel 16 in the counterclockwise direction. As has been noted above, the screw member 14 is staked as at 33 to prevent turning the screw member 14 out far enough to strike the inner end of the bore 35 and force the barrel 16 off the sleeve 25.

My eraser holder is likewise adapted to accommodate a flat, rubber eraser in lieu of the fiber glass eraser described above. For this purpose, I prefer to use a rubber eraser 60 as illustrated in Figure 7 which, in the preferred form, is made of a composition of rubber and glass although an ordinary rubber composition can be used. The eraser 60 is preferably proportioned so that it will fit snugly in the grooves 43 contained within the portion 15. The grooves 43 thus support the eraser 60 throughout its length, thereby preventing buckling of the eraser 60 when it is propelled outwardly. The length of the eraser 60 may be substantially the length of the housing 15 so that when it is assembled, it will project a slight distance beyond the slot 41, as illustrated in Figure 1.

I have provided a novel and inexpensive connector 61 for joining the rubber eraser 60 with the screw member 14. The connector 61 is formed of a U-shaped wire staple similar to the staples used in office stapling machines for permanently fastening papers together. However, by the use of the dies illustrated in Figure 8, I bend the staple so as to form a hook 62 which is adapted to reach around the head 31 and grasp the neck 32 of the screw member 14. The other end of the staple is driven through the eraser 60 and bent around, as at 63, Figure 9, to permanently fasten the connector 61 to the eraser 60. In order that the head 31 of the screw member 14 may be centrally located with respect to the end of the eraser 60, I prefer to insert the member 61 and fasten it at an angle, as shown in Figure 11. This positioning may be obtained by means of a guide 70 positioned adjacent the die 71, as shown in Figure 8. The die 72 is slightly higher than the die 71 so that the shoulder 73 provides a stop for positioning the end of the eraser 60 with relation to the forming parts 74 and 75 of the dies 71 and 72, as illustrated in Figures 8 and 9, thereby controlling the distance of the hook 62 from the end of the eraser 60. The shoulder 73 is formed by cutting away a portion of the die 72 projecting above the die 71 at an angle such that the shoulder 73 is perpendicular to the guide 70.

The U-shaped staple may be driven against the forming dies 71 and 72 by any conventional staple driving mechanism, which may comprise a plunger 76 sliding in a guide 77 as illustrated in Figure 9.

In using an eraser similar in shape to the

eraser 60 described above wherein said eraser is provided with a connector similar to the connector 61, the eraser housing 15 is unscrewed from the ferrule 17, the eraser 60 is inserted in the guide slots 43 in the housing 15, the head 31 of the screw member 14 is engaged by means of a connector 61 and then the housing 15 is screwed into the ferrule 17. The eraser 60 may then be propelled outward from or withdrawn into the housing 15 in a manner similar to that described for the use of the fibre glass eraser.

Although I have described a specific embodiment of my invention, it is obvious that changes in form and proportion of the parts may be made by those skilled in the art and I therefore wish to be limited only by the scope of the appended claims.

I claim:

1. A propel-retract eraser holder comprising an eraser housing provided with an axial bore for housing an eraser, an intermediate ferrule portion, means for releasably joining said ferrule to said eraser housing, a propelling member screw-threaded in said ferrule and projecting axially a substantial distance each side of said ferrule, a cylindrical boss projecting axially from said ferrule, a rotatable collar mounted on said boss, means for retaining said collar on said boss, a propeller barrel permanently attached to said collar, and cooperating means carried by said barrel and said screw for turning said screw as said barrel is rotated.

2. An eraser holder as described in claim 1 wherein said collar retaining means comprises an annular groove in the circumference of said boss located adjacent the outer end thereof and partially under said collar, said groove being formed with an inwardly slanting outer wall, and a substantially square spring clip having one open side adapted to fit into said groove, whereby said groove and said clip cooperate to retain said collar on said boss and resiliently urge said collar inwardly.

3. In a propel-retract eraser holder having a plurality of relatively rotatable longitudinal portions, propelling means contained within said holder, and means for actuating said propelling means by rotating one of said longitudinal portions relative to the second portion, in combination, an eraser housing portion releasably joined to said second portion, an axial bore extending throughout said eraser housing portion and terminating at its outer end in an oblong aperture, and a pair of internal guides comprising two oppositely disposed internal longitudinal grooves extending from the ends of said oblong aperture for substantially the length of said axial bore.

4. A case member for a refillable eraser holder adapted for accommodating either a glass fibre eraser comprising a substantially cylindrical bundle of glass fibres or a substantially flat, thin rubber eraser, said case member having a substantially cylindrical bore terminating at its outer end in an oblong aperture, and a pair of internal longitudinal guides comprising two oppositely disposed internal grooves extending from the ends of said oblong aperture for substantially the length of said bore, said grooves being adapted to receive and support said flat rubber eraser throughout its length.

5. In a propel-retract eraser holder comprising a substantially tubular case having an opening at the end thereof to allow the passage of an eraser therethrough, a second tubular member, means for rotatably joining said tubular members together, and a propelling screw operatively connected with said second member to rotate therewith for advancing and retracting said screw, in combination, a connector element located at the eraser end of said screw comprising an axially disposed neck and a circular head joined to said neck, a socket adapted rotatably to receive said head, said socket comprising a cylindrical cap having an axial aperture to accommodate said neck and a lateral T-shaped slot to allow the passage of said head and neck sidewise into said cap, and means for attaching said cap to said eraser.

6. In a propel-retract eraser holder having a substantially tubular case for containing an eraser element and screw means for feeding said eraser in and out of said case, in combination, means for connecting said eraser element to said screw comprising a head, a neck joining said head to an end of said screw, and a wire connector fastened to the end of said eraser element, said wire connector comprising a transverse U-shaped portion adapted to embrace said neck and prevent axial escape of said head, a stem portion extending substantially parallel to the axis of said head, and a staple portion extending at right angles to said stem portion, said staple portion being clinched to said eraser element.

7. A wire connector for releasably joining an erasing element to the propelling mechanism of an eraser holder, comprising a transverse U-shaped portion adapted to engage said propelling mechanism, a stem portion extending longitudinally of said erasing element, and a staple portion extending at right angles to said stem portion and adapted to be clinched to said erasing element.

RUDOLPH GEORGE ROESCH.
